TWO-WAY-REGENERATIVE REPEATER

Louis M. Potts, deceased, late of Evanston, Ill., by Martha W. C. Potts, executrix, assignor to Teletype Corporation, Chicago, Ill., a corporation of Delaware

Application September 18, 1944, Serial No. 554,637, now Patent No. 2,403,682, dated July 9, 1946, which is a division of application Serial No. 462,522, October 19, 1942, now Patent No. 2,403,679, dated July 9, 1946. Divided and this application February 28, 1946, Serial No. 650,981.

1. Claim. (Cl. 178—71)

1

This invention pertains to printing telegraph systems and particularly to a system for the transmission and reception of secret telegraph messages.

This application is a division of copending application Serial No. 554,637, filed September 18, 1944, now Patent No. 2,403,682, July 9, 1946, which latter application is a division of application 462,522 filed October 19, 1942, now Patent No. 2,403,679, July 9, 1946.

Secret signalling systems are desirable for naval, military and civil purposes wherein it is necessary that certain messages be rendered uninterceptable by unauthorized persons. The surreptitious interception of messages by unauthorized persons might be accomplished, for example, in the case of wire communication by tapping signal wires or in the case of radio transmission by receiving apparatuses tuned to the proper frequencies.

It has been proposed as exemplified by the G. S. Vernam Patent No. 1,310,719, dated July 22, 1919, to provide a system for sending enciphered messages in which the five unit Baudot code is employed. In general, the ciphering system described in the Vernam patent utilizes an arrangement wherein one set of five contacts are controlled by either enciphered or original signals and a second set of five contacts are controlled by key signals provided through the instrumentality of a key tape. The two sets of contacts are operated in synchronism to control jointly a set of five relays in order to encipher or decipher messages according to the direction of transmission.

As is well known in the printing telegraph art the individual code combinations of the five unit Baudot code are made up of a series of marking and spacing impulses which are customarily in the form of current impulses representative of marking conditions and no current impulses representative of spacing conditions. In start-stop telegraphy which is herein employed the five unit code is preceded by a start or spacing impulse and followed by a stop or marking impulse.

In order to encipher messages by the system of the present invention the elements of the original code combination are combined with the elements of code combinations provided by a key tape. In this arrangement opposite conditions

2

that is, with one element of the original code combination marking and with one element of the key code combination spacing, produce a marking signal. Like conditions, however, that is with both elements marking or both elements spacing, produce spacing signals. This presumes, of course, that each of the elements of the respective code combinations are related to each other. Thus the No. 1 element of the original code combination is combined with the No. 1 element of the key code combination, etc. To take a specific illustration let it be assumed that it is desired to encipher the letter "R" which in the Baudot code is composed consecutively of spacing, marking, spacing, marking, and spacing conditions. Let it be further assumed that the key tape with which the particular enciphering operation is to be performed occupies a position wherein it is conditioned for producing the letter "Y" combination which in the Baudot code is composed consecutively of marking, spacing, marking, spacing, and marking conditions. Under these assumed conditions the enciphering operation would result in the production of an all-marking or "letters" combination since in this case opposite conditions of all the elements of the "R" and "Y" code combinations are provided. This will be readily apparent from the following chart wherein the letter M indicates a marking condition and the letter S indicates a spacing condition.

	1	2	3	4	5
Original Signal "R"	S	M	S	M	S
Key Signal "Y"	M	S	M	S	M
Resultant Enciphered Signal "Letters"	M	M	M	M	M

It is to be understood that both the transmitting and receiving ends of a telegraph line will be equipped with identical key tapes, which during message transmission will occupy identical positions during each signal interval. A station which receives enciphered signals is thus enabled to decipher the unintelligible signals transmitted over the telegraph line by combining the enciphered signals with the key signals provided by its key tape. To illustrate a deciphering operation the example given above in connection with the enciphering operation will be continued and it will be assumed that a receiving station

received the enciphered signal; namely, "letters." The "Y" combination provided by the key tape at the receiving station can now be combined with the "letters" combination to decipher the enciphered signal to thereby reproduce the original signal "R" as clearly shown in the following chart.

	1	2	3	4	5
Enciphered Signal, "letters"	M	M	M	M	M
Key Signal "Y"	M	S	M	S	M
Original Signal "R"	S	M	S	M	S

The use of mechanically controlled and operated signalling arrangements have demonstrated advantages not obtainable in systems which are for the most part electrically controlled. Electrically controlled systems which usually include receiving and transmitting commutator distributors and relay controlled contact arrangements, while advantageous for certain requirements, do not operate with the efficiency and comparatively slight maintenance afforded in mechanical systems. A mechanical enciphering arrangement employing permutation code combinations with its attendant advantages over electrically controlled systems has thus far not been proposed. Mechanical enciphering systems are particularly desirable for the transmission of secret messages wherein it is advisable that signal distortion be kept to a minimum and that maintenance troubles do not delay communicating operations.

Accordingly the primary object of the present invention is the provision of a simple, reliable and practical system and apparatus for rendering messages unintelligible to unauthorized persons.

Another object of the invention is to provide a system and apparatus for precluding the unauthorized interception of messages by mechanical operations established in response to the respective control conditions.

A further object of the invention is the provision of a portable mechanically operated ciphering unit which may be readily associated with standard printing telegraph apparatus used for telegraphic communication.

A feature of this invention is the employment of directional switching means for automatically conditioning a ciphering unit for either enciphering or deciphering operations dependent upon the direction of transmission.

An additional feature of the present invention is the provision of a mechanical enciphering unit in the form of a regenerative repeater.

Other features and advantages of the invention will appear as the description progresses and accordingly the invention should not be limited by the specific recitals appearing above.

The invention herein described utilizes a portable mechanical ciphering unit in the form of a regenerative repeater resembling the regenerative repeater illustrated in Patent No. 2,105,173 to W. J. Zenner et al. dated January 11, 1938. The unit includes a signal transmitting contact lever operable sequentially by a series of selector bars in accordance with the joint control exercised over the bars by a series of levers which may be under the direct control of a key tape or in a modification of the invention under the control of a set of five code magnets and a single armature lever controlled by a selector magnet which may respond to either enciphered or deciphered signals. It is understood, of course, that other equivalent means of control may be employed.

The proposed construction includes a com-

plete circuit system for operation of the unit which controls directional switching means for automatically enciphering or deciphering messages dependent on the direction of transmission. In one form of the invention a direction switch bar is employed which is operated either to one of two positions depending on the direction of the signals. The second form of directional switching employed features the use of a contact operating lever having a pair of transmitting contacts and a switching system which renders one or the other of the contacts effective for transmission according to the direction of signalling.

All necessary equipment for the ciphering unit will be contained in a small portable receptacle that may be conveniently carried for use at locations having standard printing telegraph apparatus. A set of plugs are included with the unit to enable the unit to be quickly and easily associated with standard telegraph apparatus.

The invention may be more readily understood from the following detailed description and the drawings wherein:

Fig. 1 is a circuit diagram embodying the present invention,

Fig. 2 is a front elevational view of the structure according to the present invention; and

Fig. 3 is a sectional view taken on line 3—3 of Fig. 2.

The present invention features the use of code magnets in place of the tape sensing levers employed in the first described embodiment of the invention and also the use of a transmitting contact member having a pair of contact arms, only one of which is effective at a time dependent upon the direction of transmission.

Since in the instant embodiment of the invention the tape sensing levers for shifting the code bars have been omitted, a second cam sleeve is unnecessary for the sensing and tape stepping functions. In this embodiment the direction switch bar has also been omitted and switching is now performed by means of a relay system.

Referring now to the drawings, 334 represents a continually driven shaft. The release of a sleeve 341 is accomplished by a selector magnet 364 and clutch mechanism, except that the release of the sleeve 341 is accomplished solely by the selector magnet 364 in view of the fact that the start magnet has been dispensed with. Sleeve 341 is released by the operation of gate latch 383 which acts upon the stop arm 342 integrally associated with the cam sleeve 341. Cam sleeve 341 carries a series of five transmitting cams 351 which are sequentially operable to control a series of five transmitting code bars 352. Cam sleeve 341 also carries a start cam 353 for controlling the start bar 354, a cam 355 for controlling the stop bar 356 and a contact operating cam 357, the purpose of which will hereinafter appear.

The code bars are controlled by a set of code magnets 361 which may be operated from a key tape transmitter 362 (Fig. 1). In response to signals from the key tape transmitter 362, armature levers 363 associated with respective code magnets 361 are moved to the left or right as viewed in Fig. 2 to enable their associated code bars 352 to assume similar positions. Similarly, selector magnet 364 positions the armature lever 366 to the left or right as pictured in the same view to cooperate with the notch 390 in each code bar to enable the code bars to tilt to a counter-clockwise or clockwise position. This tilting operation is provided by the operation of the transmitting code cams, which sequentially operate

associated T-shaped operating levers 399. A Y-shaped lever 314 is moved to its marking or spacing position under the combined influence of signals received by the selector magnet 364 and by the code magnets 361, to operate the pair of contact arms 317 to their marking or spacing position, to control the signal contact mechanism 318. As indicated in Fig. 1, the contact mechanism 318 comprises two sets of retransmitting or repeater contacts 426 and 446, one set being associated with each of the pair of arms 317. The contacts 426 are effective when signals are incoming from a remote station 404 (Fig. 1) through the ciphering unit 400 to the local station 401, and contacts 446 are effective when signals are outgoing from local station 401 through the ciphering unit 400 to the remote station 404. Just before the end of each revolution of cam sleeve 341, contact cam 357 will move the bell crank lever 380 in a counterclockwise direction about its pivot 381 (as viewed in Fig. 2) to operate the make-before-break contact 382 for a purpose which will hereinafter appear, which position is maintained during the rest or stop period.

It will be understood that, as signals are received by the selector magnet 364, a start impulse will precede each code combination to cause the release of the cam sleeve 341. This causes the start cam 353 to operate the start bar 354 for sending a start or no-current impulse by means of the contact operating arm 317. Immediately thereafter, the five code combination impulses will be transmitted under the control of the code bars 352 associated with their respective code bar cams 351. At the termination of the transmission of the code combinations stop cam 355 operates to position code bar 356 to control the contact operating arm 317 to its marking or current position.

Referring now particularly to Fig. 1, the circuit for operating the modified form of scrambling unit will be described in detail. A local station 401 is equipped with a combination keyboard transmitter and printer of any well-known type, which is designed to communicate by means of central offices or exchanges 402 and 403 with a similarly equipped distant station indicated at 404, which is provided with a ciphering unit 405, identical in construction with the ciphering unit employed in the modified form of the invention. When it is desired to attach the ciphering unit to any standard telegraph printing station, plug and jack connections may be made at 406 and 407 which will connect the local station 401 to a switch 408 and similarly connect the loop from the exchange 402 to the same switch at the plug connection 407. When switch 408 is positioned to its up position, signals may be transmitted directly from station 401 to the central office 402 without any enciphering operation taking place. However, when it is desired to encipher the signals, the switch 408 may be manually positioned to its downward position and for the purposes of the present description, it will be presumed that the switch has assumed such a position. In addition the ciphering unit will be provided with a plug 409 which may connect with any convenient alternating current outlet to provide the current to a motor 411. The unit will be further equipped with a rectifier indicated generally at 412 which will provide positive current over conductor 413, and negative current over conductor 414, as is well known in rectifying circuits of this type.

It will be presumed for the first portion of the

present description, that the local station 401 desires to transmit enciphered messages to the remote station 404. Normally, the selector magnet 364 in the rest condition of the apparatus is energized, as is common practice in start-stop telegraphy, over the following circuit: From negative conductor 414, over conductor 415, through selector magnet 364, over conductor 417, through tongue 418 of receiving relay 419 (now de-energized), over conductor 421, and over conductor 422 to positive conductor 413. When the apparatus at the local station 401 is in its rest position, winding 423 of the double wound repeating relay 424 is energized over the following circuit: From positive conductor 413, over conductor 425, through contact 426, over conductor 427, through winding 423 of relay 424, over conductor 428, through tongue 429 of switch 408 (now in its down position), over conductor 430, through the printer apparatus at station 401, over conductor 432, tongue 433 (in its down position), and over conductors 469 and 415, to the negative conductor 414.

When, therefore, local station 401 transmits the start impulse, the just described circuit is broken at the transmitting contacts 410 at the local station 401, in a well-known manner, causing contact tongue 431 associated with the double wound relay 424 to be released. When this occurs, the following circuits are established: From negative lead 414, over conductor 432, through relay 433 (which now becomes energized), over conductor 434, through winding 435 of the double wound relay 419, over conductor 436, through contact tongue 431 (now released) of relay 424, and over conductor 422 to the positive lead 413. Thus, at this time both relay 433 and relay 419 become energized. When relay 419 becomes energized, tongue 418 associated therewith is attracted and consequently the previously described circuit to the selector magnet 364 is broken, causing the release of the cam sleeve 341 for a cycle of operations, in a manner which is well-known in start-stop telegraphy. When relay 433 operates, it locks up over the following circuit, since as cam 357 commences to rotate, the make-before-break contact 382 is permitted to operate to close its contact 384 and open its contact 385 to enable the establishment of the just mentioned locking circuit of relay 433: From positive conductor 413, over conductor 437, through contact 384 (now closed), over conductor 438, through tongue 439 of relay 433, through the winding of relay 433 and over the conductor 432 to the negative lead 414. In addition the double wound repeating relay 441 is locked up over the following circuit in order to prevent the repetition of signals back into the originating circuit when outgoing signals are being transmitted (sometimes called echo suppression): From negative potential lead 414, through the right-hand locking winding of repeating relay 441, over conductor 443, through tongue 444 of relay 443 (now closed), over conductor 445, over conductor 422, to positive lead 413. Since the winding 454 of repeating relay 441 is in the same circuit with contacts 446, and if relay 441 was not thus locked-up, said relay would be operated in consonance with the vibrations of contact 446, thus operating its armature 482 to disturb the control of selector magnet 364 by repeating relay 424. In a similar manner, the repeating relay 424 will be locked up in a circuit to be described later, in order to prevent the repeating relay 424 from sending signals back into the originating circuit while

incoming signals are being received from a remote station.

At this time, contact 426 is rendered ineffective for transmission and conversely, contact 446 is conditioned for operation in the following manner: The afore-described energizing circuit for the double-wound repeating relay 424 is provided with a shunt or by-pass to positive battery 413 at junction 420 on conductor 427, so that after the first start impulse has become effective, the contacts 426 will be shunted. This shunt circuit extends from junction 420 over armature 447 (when attracted as previously described), over conductors 445 and 422 to positive source 413. It is therefore found that when contact arms 317 move to their marking positions, the closure of contact 426 will be ineffective, so as not to interfere with the outgoing signals, inasmuch as the circuit to contacts 426 has now been shunted out of the transmitting circuit. Transmitting contact 446 is rendered effective for transmission at this time since its shunt circuit (hereinafter described), which is normally closed, is now opened, inasmuch as contact tongue 448 of relay 433 is attracted to open the shunt circuit for said transmitting contact so that signals may be repeated thereby to the distant station. Normally the shunt circuit for contact 446 is as follows: Over lead 455, through closed contact 448 of unoperated relay 433, and over lead or conductor 497.

It is assumed that signals from station 401 are being repeated by the repeating relay 424 which, by opening and closing its contacts 431 causes the signals to be repeated again by the energization and de-energization of the winding 435 of the double-wound relay 419. Therefore, selector magnet 364 will be similarly conditioned so that its armature lever 366 cooperates with the armature levers 363 of the code magnets 361 to control the Y-shaped transmitting lever 314. The central office 402 will transmit signals to station 404 as its loop circuit extends through the contact 446. Thus the loop circuit is conditioned to receive marking and spacing impulses according to the operation of the Y-shaped lever 314. This circuit is as follows: From conductor 451, through tongue 452 of switch 408, over the conductor 453, through the winding 454 of double-wound repeating relay 441, over conductor 455, to the contact 446, over conductor 456, through tongue 457 of switch 408 to the loop conductor 458 which leads to the central office identified as 402. It will be understood that at the end of each cycle of operation the make-before-break contact 382 will operate to open the locking circuit extending over conductors 437 and 438 to the relay 433 so that the circuit will be returned to its normal condition.

The operation of cam 351 at the termination of each cycle of operation, through the operation of contact 382, causes the energization of stepping magnet 461 which steps the key tape at the key transmitter 362 to a new operating position. This circuit is as follows: From positive conductor 413, over conductor 437, through contact 385, over conductor 462 associated with cable 463, over conductor 464, through stepping magnet 461, over conductor 465, over conductor 466, over conductors 467, 468, and 469, then over conductor 415 to the negative lead wire 414. Therefore, during each cycle of operation stepping magnet 461 will operate to step the tape to a new position.

The code magnets 361 which are controlled by the key tape transmitter 362 are controlled by the now to be described circuit. From positive

lead 413, over the conductor 471, and over conductor 470 to the key tape bus bar 472, which is in this manner normally provided with positive potential. Thus, when a tape feeler in the tape transmitter 362 senses a perforation, a circuit will be established to its respective code magnets as follows: From positive bus bar 472, over the particular conductor 473 associated with the particular feeler pin, over conductor 473a, thence through the associated code magnet 361 to conductor 467 which acts as a negative bus bar over the following circuit: Over conductor 468, over conductor 469, and then over conductor 415 to negative lead 414. Therefore, according to the marking and spacing conditions of the key tape associated with the key transmitter 362 code magnets 473 will be energized under marking conditions and de-energized under spacing conditions.

The circuit will now be described in connection with the receipt of signals from the outlying or remote stations 404 which are enciphered by means of the ciphering unit 405 and then transmitted through central offices 403 and 402 to the local station 401. At this time the circuit to the normally energized repeating relay 441, which is similar to the normally energized repeating relay 424, is broken upon the receipt of a start or spacing impulse from the remote station 404. This initiates a cycle of operation by the release of cam sleeve 341, as has been previously described in detail. The circuit extending to the repeating relay 441 is as follows: From source of potential at central office 402, over conductor 458, through contact 457 of switch 408, over conductor 456, through contact 446, over conductor 455, through operating winding 454 of the double-wound repeating relay 441, over conductor 453, through tongue 452 of switch 408, over conductor 451 to the other source potential at the central office 402. At this time, when the start impulse is transmitted from the remote station 404, relay 441 will become de-energized and its tongue 482 will be released to establish a circuit for relay 419 and relay 484 as follows: From positive lead 413, over conductor 422, through tongue 482 of repeating relay 441, over conductor 485, through the winding 483 of relay 419, over conductor 486, through the winding of relay 484, over conductor 492 to the negative lead 414. When relay 484 becomes energized, it is locked up as cam 351 operates to close the contact 384 as follows: From positive lead 413, over conductor 437, through contact 384, over conductor 438, through tongue 491, through the winding of relay 484, over conductor 492 to negative lead 414. Operation of relay 484 also causes the locking up of the repeating relay 424 to prevent this relay operating at this time in order that its contact tongue 431 may not interfere with signals in the circuit. This circuit is as follows: From positive lead 413, over conductor 422, over conductor 445, to contact tongue 492 of relay 484, over conductor 493, through the locking winding 494 of relay 424, over the conductor 495, and over the conductor 492 to the negative conductor 414.

After the first start impulse has become effective, transmitting contact 446 is bridged over the following shunt circuit already described above: Over conductor 455, through contact 448 of relay 433 (inasmuch as relay 433 is now de-energized), then over conductor 497. It is thus apparent at this time that the operation of contact 446 thereafter will produce no harmful result in the cir-

cuit in view of the shunt circuit provided therefor. Contact 426, however, is now free to operate, due to the fact that contact 447 of relay 433 is now open and the previously described circuit does not shunt out the contact 426.

Therefore, a circuit is made to repeat deciphered signals to the local printer 401 as follows: From positive lead 413, over conductor 425, through contact 426 (now operating), over conductor 427, through winding 423 of relay 424 (now locked), over conductor 428, through tongue 429 of switch 408, over conductor 430, through the printer at station 401, and on a return path over conductor 432, through tongue 433, over conductor 469 and over conductor 415 to the negative source of potential 414. It is further apparent at this time that selector magnet 364 will be operated according to incoming enciphered signals received from remote station 404 as relay 441 operates its tongue 482 and causes the operation of the double-wound repeating relay 419, which by its contact tongue 418 repeats the incoming signals to the selector magnet 364. As has already been mentioned, when cam 357 reaches its stop position the relay circuits are broken and the system is conditioned for reception in either direction.

It will be understood that various changes and modifications may be made in the present invention without departing from the spirit and scope thereof, and the invention should accordingly be limited only by the appended claim.

What is claimed is:

In a two-way regenerative repeater, a first line section, a second line section, a signal repeating
